SPARK PLUG

August E. Anderson, Montclair, N. J.

Application August 3, 1935, Serial No. 34,624

5 Claims. (Cl. 123—169)

My invention relates to spark plugs for internal combustion engines and has for its main object to provide a porcelain insulator unit having both main and ground electrodes permanently fixed therein with accurately adjusted spark gap, thus making the unit replaceable as a whole in the metal housing. This has the advantage that in case of injury to the porcelain, as by cracking or breaking making it useless, it is possible to insert 5 in an old metal housing a new porcelain unit, instead of putting in a completely new spark plug. In this manner a considerable saving in costs to the user is made, because the metal housing may be used over and over again and only new porcelain need be obtained.

Another and very considerable advantage is also gained by the permanently set spark gap which is adjusted before the porcelain unit leaves the factory. The ground electrode, which consists of a ring or gasket with a projecting finger, 20 is namely permanently secured near the inner end of the porcelain and the finger bent over towards the end of the slightly protruding central or main electrode to obtain the desired spark gap with sliding spark. The ground electrode gasket may be secured on the porcelain either by 25 cement or other adhesive or by screws, rivets or prongs.

Still another advantage of my spark plug is obtained by the feature that the spark gap is arranged deep in the metal housing and above the threaded portion thereof, that is, above the water jacket. This prevents cracking of the porcelain.

These and other advantages are obtained by my invention which will be further explained in the following description and illustrated in the accompanying drawing, in which:

Figure 1 shows an axial section of my spark plug;

Fig. 2 a bottom plan view of Fig. 1;

Fig. 3 a perspective view of the combined gasket and ground electrode used;

Fig. 4 a modified form of the ground electrode;

Fig. 5 a fragmentary elevation of the inner end 45 of the porcelain unit, with the ground electrode of Fig. 4 in position;

Fig. 6 a similar view to Fig. 5 with another securing means for the ground electrode, and

Fig. 7 a front elevation of the porcelain unit 50 with both electrodes and upper gasket secured in position as ready for the market.

In the drawing reference numeral 10 represents the body of the metal housing with its securing nut 11 for the porcelain insulator or di- 55 electric 12.

A characteristic feature of the invention is that the inner end of the porcelain terminates with a tapering shank 13 quite a distance in from the end 14 of the housing 10 when assembled therein and above the threaded portion itself. The main 5 electrode 15 which consists of a straight pin extending all the way through the porcelain protrudes slightly with its spark point 16 beyond the end of the tapering shank 13 of the porcelain. The main electrode is threaded as at 17 in the 10 outer end of the porcelain in the usual manner and is provided with a screw cap 18 for securing the lead-in wire.

The porcelain 12 has an enlarged body portion 19 with upper and lower shoulders for gaskets 20 and 21 for which seats are provided in the securing nut 11 and the housing 10 respectively, whereby the porcelain is firmly secured in the housing 10 when the nut 11 is drawn up tightly.

The upper gasket 20 is of conical shape as is 20 also the lower gasket 21, which latter forms the ground electrode and is somewhat similar in construction to that in my co-pending application Serial No. 738,345, August 3, 1934 and an improvement thereon; that is, it is provided with one or 25 more fingers 22, bent inwardly towards the end 16 of the main electrode 15 which end 16 only slightly projects beyond the shank 13 of the porcelain so as to form a spark gap 23, well inside the open end of the metal housing. The spacing of 30 the electrodes is fixed by the end of shank 13 of the porcelain. In order to assure the accurate position of the finger 22 to produce the desired sliding spark and a permanent width of the spark gap, an annular ledge 24 spaced therefrom and 35 of less height than the tapered shank 13 and having its base diameter equal to the corresponding inner diameter of the gasket or ground electrode 21 is provided so as to accurately locate the parts when assembled. The finger 22 is bent so 40 as to follow the conical surface of the ledge 24 and project beyond its end terminating level with the end of the shank 13. Furthermore, the two gaskets 20 and 21 are permanently secured on the shoulders of the body portion 19 of the porcelain. 45 This may be accomplished by means of an adhesive 25, Fig. 3, or by a number of prongs 26 shown on the ground electrode 27 in Figs. 4 and 5. These prongs 26 are intended to be sprung over the end of the body portion 19 of the porcelain whether the same is smooth-faced or furnished with corresponding grooves for accommodating the prongs.

In Fig. 6 is indicated still another way of firmly and permanently securing and positioning the 55

ground electrode 28 on the body portion 18 of the porcelain, namely, by rivets, pegs, screws 29 or the like.

In Fig. 7 is shown the porcelain electrode unit 5 assembled as sold on the market and which consists of the following parts: porcelain 12, main electrode 15, screw cap 18, gasket 20 and ground electrode 21 with finger 22. All that is needed in replacing a broken or injured porcelain is then 10 to unscrew the securing nut 11, take out the old porcelain and put in a new porcelain-unit and secure it in place by tightening up the nut 11. No adjustment whatsoever will be necessary since the correct spark gap has already been set before 15 the unit leaves the factory.

The renewal of spark plugs in this manner is considerably less costly to the user and assures accurate width of the spark gap without special adjustment.

20 Moreover, the exchange of the porcelain units can be performed in a very short time.

It should be noted that the seat for the ground electrode is located high up in the metal gasket and about level with the octagonal tightening 25 collar 30. As a consequence, the spark gap is also located well away from the open, threaded end 14 of the metal housing 10.

It should be understood that the invention is not limited to the details of construction here 30 shown and disclosed, but that those may be varied widely without departing from the spirit of the invention as defined by the claims.

I claim:

1. In a spark plug having a metal housing and 35 a dielectric, and a slightly protruding main central electrode in said dielectric; a ground electrode in the shape of an annular gasket with an inwardly bent finger adapted to form a sliding spark with said main electrode, and means for 40 permanently securing said ground electrode on said dielectric with preadjusted spark gap, thereby providing a replaceable unit for the spark plug.

2. In combination with a metal spark plug 45 housing, a unit comprising a porcelain adapted to be assembled in said housing, a central electrode secured in the porcelain so as to slightly project with its point beyond the end thereof, a gasket ground electrode having an inwardly bent 50 finger adapted to form a sliding spark with said

point, a ledge on the porcelain adapted to accurately locate the gasket with preadjusted gap between said electrodes and means for permanently securing said gasket electrode on said porcelain.

3. In combination with a metal spark plug housing, a unit comprising a porcelain adapted to be assembled in said housing, a central shank on said porcelain, a main electrode secured in the porcelain so as to slightly project with its point 10 beyond the end thereof, a gasket electrode having an inwardly bent finger adapted to form a sliding spark with said point, a ledge on the porcelain having a base of the same diameter as said gasket in order to accurately locate the finger 15 with preadjusted gap between the electrodes and means for permanently securing said gasket electrode on said porcelain, said ledge forming a support for said gasket and finger.

4. In combination with a metal spark plug 20 housing, a unit comprising a porcelain adapted to be assembled in said housing, a central shank on said porcelain, a main electrode secured in the porcelain and having a slightly projecting point beyond the end of said shank, a gasket 25 electrode having an inwardly bent finger adapted to form a sliding spark with said point, an annular ledge on the porcelain providing a cooling space around said shank adapted to accurately locate the gasket electrode with preadjusted gap 30 between said electrodes and means for permanently securing said gasket electrode on said porcelain.

5. In combination with a metal spark plug 35 housing, a unit comprising a porcelain adapted to be assembled in said housing, a central electrode secured in the porcelain having its point slightly protruding beyond the end of the porcelain, an annular ground electrode having an inwardly bent finger adapted to produce a sliding 40 spark with said point, a ledge on the porcelain adapted to accurately locate the ground electrode with preadjusted gap between said electrodes and to provide an annular cooling space therefor, and means for permanently securing said ground 45 electrode on said porcelain, said housing being provided with a seat for the unit in such a position that the spark gap is located as far back as possible from the open end of said housing.

AUGUST E. ANDERSON. 50
